UNITED STATES PATENT OFFICE

MARTIN J. FELD, OF PHILADELPHIA, PENNSYLVANIA

DESIGN FOR A SWEATER

Application filed May 23, 1930. Serial No. 35,734. Term of patent 3½ years.

To all whom it may concern:

Be it known that I, MARTIN J. FELD, a citizen of the United States, residing at Philadelphia, in the county of Philadelphia and State of Pennsylvania, have invented a new, original, and ornamental Design for Sweaters, of which the following is a specification, reference being had to the accompanying drawing, forming part thereof.

I claim:

The ornamental design for a sweater as shown.

MARTIN J. FELD.
